SPEED REGULATOR FOR AUTOMATIC GUNS

Samuel G. Green, Gray, Ga.

Application October 14, 1940, Serial No. 361,095

10 Claims. (Cl. 42—3)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a gas regulator for automatic weapons actuated by gas.

The principal object of this invention is to provide a gas regulator having a gas chamber ported direct to atmosphere and so proportioned to the port and the displacement of a piston in communication with the chamber that the ratio of expansion of the gas admitted to the chamber with respect to the piston displacement will be such as to impart a uniformly increasing acceleration to the piston, maintain the temperature of the gas in the chamber sufficiently high for a sufficient period of time to effect combustion of combustible particles passing to the chamber, and be of such volumetric capacity as to receive an excess of gas so that the volume passing to atmosphere by way of said port will not sufficiently minimize the effect of the initial volume received in the chamber as to reduce the pressure below a critical operating pressure.

A further object of the invention is to provide a gas regulator which will have a minimum adjustment, as to gas ported to atmosphere from the gas chamber, effect actuation of the weapon in accordance with a predetermined standard when the lowest powered ammunition designed for use with the weapon unto which the regulator is attached is used, and which is adjustable to a maximum adjustment to increase said porting effect when higher powered ammunition is used for the purpose of effecting duplication of said predetermined standard whereby a uniform operating power source is maintained in service irrespective of the type of ammunition used.

A still further object of the invention is to provide a gas regulator wherein a gas chamber communicating with an operating piston is ported to atmosphere and is of such volume relative to the piston displacement and port that the pressure built up in the chamber will be relatively gradual thus obviating the shock, or impact imparted to a weapon where the pressure is built up instantaneously in a gas chamber by sudden arrestation of expansion of the entering gases.

Another object of the invention is to so proportion the volume of the gas chamber of a gas regulator that the elasticity of the gases may be utilized in absorbing shock.

Still another object of the invention is to provide a gas chamber in a gas regulator wherein

expansion of the entering gases will be permissible over a relatively long period of time thereby providing for application of the power source over a correspondingly long period with consequent more uniform application thereof and accompanying increased uniformity of operation of the weapon.

A still further object of the invention is to provide a gas regulator having a gas chamber provided with an operating piston formed of such material that the piston may broach carbon or fouling depositions from the zone of the cylinder in which the piston works, and deposit the broached matter in the gas chamber to be exhausted therefrom by inherent action of the regulator.

A further object of the invention is to form the operating piston head which cooperates in forming the structural combination of the gas regulator of a material harder than carbon and capable of maintaining a red hardness under heat in the vicinity of 1500° F. so that it may serve as a broach to broach its cooperating cylinder portion clear of carbon or similar fouling deposits.

A still further object of the invention is to provide a gas regulator that will maintain uniformity of the operating cycle of a weapon unto which it is attached whereby the adaptation of a cyclic rate reducing mechanism may be facilitated.

The specific nature of the invention as well as other objects and advantages thereof will clearly appear from a description of a preferred embodiment as shown in the accompanying drawings in which:

Fig. 1 is a longitudinal sectional view of a preferred form of the gas regulator of this invention, showing the manner in which it is attached to the muzzle end portion of the gas cylinder tube;

Fig. 2 is a plan view of the muzzle end portion of the regulator shown in Fig. 1;

Fig. 3 is a sectional view taken generally on the line 3—3 of Fig. 1;

Fig. 4 is a longitudinal sectional view showing a modified form of throttle valve for use in the regulator of Fig. 1;

Fig. 5 is a longitudinal sectional view showing a modified form of gas regulator;

Fig. 6 is a view similar to Fig. 5 showing a further modified form of gas regulator.

Reference is now made to the drawings where in corresponding elements are identified by cor-

responding characters of reference throughout the views, and in particular to Fig. 1 which discloses a fragmentary portion of a barrel 10 and gas cylinder tube 11 affixed adjacent its muzzle end to the barrel, as by the front gas cylinder tube bracket 12.

A gas cylinder tube sleeve 13 provided with an exterior annular shoulder 14 intermediate its ends is exteriorly threaded rearwardly of the shoulder 14 as indicated at 15 for interthreaded engagement with complementary threads 16 provided on the interior end portion of the gas cylinder tube 11. Forwardly of the shoulder 14 the gas cylinder tube sleeve 13 is of a greater outside diameter than the rearwardly extending portion bearing the threads 15 so as to facilitate the provision of an annular valve seat 17 extending forwardly and outwardly from the surface defining the bore 18 of the sleeve. To demountably secure the sleeve 13 in assembled relation with respect to the gas cylinder tube 11 a lock washer 19 having a plurality of spaced deformable locking tabs 20 is interposed between the shoulder 14 of the sleeve and adjacent end of the gas cylinder tube 11 with provision made, such as 25 the recesses 21 and 22 in the shoulder 14 and gas cylinder tube 11, respectively, to have the tabs 20 deformed thereinto for interlocking the sleeve and gas cylinder tube.

Communication between the bores of the barrel 10 and sleeve 13 is established by means of a gas port 23 provided in the barrel 10, front gas cylinder tube bracket 12, gas tube cylinder 11, and a port 24 in the sleeve 13 which is adapted to be aligned with the port 23. To ensure expeditious assembly of the sleeve 13 with the gas cylinder tube 11 in such manner that the gas ports 23 and 24 will be properly aligned, the topmost locking tab 20 of the lock washer 19 is so dimensioned with respect to the remaining tabs 20 that it alone may be deformed into the corresponding topmost recess 22 which is aligned with the gas port 23, and is provided with an alignment symbol 25 so disposed as to be visible when the tab is deformed into locking relation with the gas cylinder tube as clearly shown in Fig. 2. A coacting alignment symbol 26 is suitably inscribed or otherwise formed upon the shoulder 14 of the sleeve 13 whereby when the shoulder is brought into abutting or substantial abutting relation with the lock washer 19 with the alignment symbols 25 and 26 in proper alignment the gas ports 23 and 24 as shown in Fig. 1, will be properly aligned. While the topmost tab 20 has been described as bearing the alignment symbol 25 it is to be understood that such description is to be by way of illustration and not of limitation, as the tab 20 bearing symbol 25 may be circumferentially disposed with respect to the gas cylinder tube 11 as desired, although in practice the location described and shown in Figs. 1 and 2 is to be preferred.

A piston 27 is mounted within the gas cylinder tube 11 for reciprocable movement and is provided with a piston head generally indicated at 28 which comprises a piston ring or rings 29 secured to the body of the piston by the ring securing stud 30 as shown in Fig. 1. The piston occupies a position in the "ready to fire" condition of the weapon wherein the piston ring 29 will be within the rear end portion of the sleeve 13, which latter portion as more particularly shown in Fig. 1 is of slightly reduced diameter so as to form an annular ledge 31 in the plane of the muzzle or forward end of the piston ring in "ready to

fire" position for a purpose hereinafter made apparent. As well understood in the art the piston is kept in proper alignment within the gas cylinder tube 11 by bushings interposed in any suitable fluid sealed manner between the piston and bore of the tube, as for example, the bushing indicated at 32, and communication between the interior of the tube 11 and atmosphere rearwardly of the piston ring 29 is established by way of ports 33 so as to obviate the creation of a back pressure within the tube 11 against which the bushing and piston will have to work and to provide ready escape for any gases by-passing the piston ring 29 from the gas chamber 45. If desired the piston ring securing stud 30 may be affixed to the body of the piston by any suitable detachable securing means such as the self securing cross pin indicated at 34.

The forward end portion of the sleeve 13 is closed by a throttle valve 35 which is formed with a truncated conical surface 36 complementary to the valve seat 17. As shown the valve 35 is formed with a longitudinally extending centrally positioned port 37 terminating in an outwardly flared entrance portion 38 adjacent its end of truncation. The valve 35 is of reduced diameter forwardly of its truncated conical portion and the reduced portion is fixed within the bore in an inturned flange at one end of a valve cage 39, as by means of staking indicated at 40. The inturned flange of the valve cage is provided with a plurality of circumferentially spaced ports 41 outwardly of the valve, and the cylindrical portion 42 arranged to surround the valve and the cylindrical portion is internally threaded as indicated at 43 to be interthreaded with the threads 44 formed on the enlarged portion of sleeve 13 forwardly of the shoulder 14. In the arrangement disclosed the valve 35 may be adjusted from seated relation as shown in Fig. 1 to a position giving the desired throttled passage leading from the piston clearance or gas chamber 45 defined by the piston 27, bore 18 of sleeve 13, and valve 35, past the valve through the ports 41 in the valve cage 39 to atmosphere. To retain the valve 35 in adjusted position relative to sleeve 13 there is a spring detent 46 affixed to the valve cage 39 as by the dove tail joint 47 shown in Fig. 3, which has a detent finger 48 adapted to resiliently engage within any one of a plurality of recesses 49 formed in the shoulder 14 of the sleeve.

Although the piston ring 29 in the embodiment shown in Fig. 1 is comprised of spaced ring members joined integrally by a ring member of smaller outside diameter it will be understood that these elements may be made separately or organized in a different arrangement. It is preferable to fabricate the ring 29 of a material having a hardness greater than that of carbon and which will maintain its red hardness under heat up to or in excess of 1500° F. so that the ring will serve to broach any carbon or other fouling deposits tending to collect within the sleeve 13 whereby the sleeve may be kept clear of deposits tending to retard or entirely freeze movement of the piston. I have found that a chromium-cobalt-tungsten alloy steel serves the purpose admirably, and that when used in combination with an aluminum-bronze alloy sleeve 13 having a chamber 45 with a proper expansion ratio with respect to the displacement of the piston head 28, will function without entailing the necessity for taking the gas regulator apart for cleaning for periods far superior in point of time than the

regular periodic cleaning required of certain other parts of the weapon.

An important feature of the invention resides in the establishment of what I term the expansion ratio of the regulator, which is the ratio between the piston clearance 45 with the valve 35 fully seated and the displacement of the piston head 28. I have found by experiment that this ratio must fall within a range between the critical ratios of 4:1 and 16:1, depending upon the stroke of the piston and work required thereof in actuating the mechanism of the weapon, to maintain the requisite volume of gas in the chamber 45 to work upon the piston head, maintain the temperature of the volume sufficiently high to effect combustion of combustible particles passing from the barrel to the chamber, be of sufficient volume to obtain the elastic characteristics of a fluid medium thereby eliminating shock and hammer effect, and be of such excess volume as to permit the passage of gas from the chamber, as by port 37, for the purpose of clearing the chamber of particles that are either not combustible or have been cleared by the broaching action of the piston ring 29 after deposition upon the walls of the chamber and to build up pressure gradually. If the ratio is any less than 4:1 gas entering chamber 45 will strike the piston head 28 a hammer blow, thus delivering a shock to the weapon by reason of the insufficient volume of chamber 45 to permit admission of a sufficient volume of gas to absorb the shock through the elasticity of its own volume and the necessary rapid build up of operating pressure with such small volume, and moreover, the volume of gas will be insufficient in quantity to provide for sufficient expansion to do the necessary work upon the piston head and perform its scavenging function in removing particles from the chamber through port 37 without falling below the critical pressure requisite to drive the piston. If the ratio is any greater than 16:1 the action becomes "lazy" due to the large volume to expand, and more important than under conditions of a smaller ratio so much gas will be "tapped" from the barrel as to materially reduce its propelling effect upon a projectile therein with consequent reduction of muzzle velocity of the weapon.

In practice the expansion ratio for the particular weapon is determined in accordance with the stroke of the piston, work to be done by the piston, size of the port 37 in valve 35 and type of ammunition. The ratio is selected on the basis of the lowest power ammunition to be used with the weapon, and amount of gas necessary to be ported through the valve 35 to thoroughly clear the chamber 45 of all loose particles while valve 35 is fully closed. With the ratio established on this basis the cyclic rate may be controlled within limits by adjusting valve 35 to pass more or less gas from the chamber 45 through the passage between the valve and valve seat 17 and ports 41 to atmosphere, likewise by adjusting valve 35 the same operating conditions may be made to prevail with the use of a higher powered type of ammunition as are obtained with the lowest power ammunition thereby providing for establishment of a uniform cyclic rate of the weapon when fired with any of various powered ammunitions designed for use therein.

In operation and with the barrel 10, gas cylinder tube 11, bracket 12 and piston 27 assembled as shown in Fig. 1 the gas regulator above described is assembled as follows: The lock washer 19 is inserted upon the end portion of sleeve 13

5 bearing threads 15 in such manner that the deformable tab 20 may be deformed into its cooperating recess 22 with the alignment symbol 25 rendered visible. The sleeve is then secured to the end portion of the gas cylinder tube 11 by interthreading its threads 15 with the threads 16 of the gas cylinder tube and threading the sleeve therein until the shoulder 14 approaches contiguity with the end of tube 11, at which time the 10 tab of washer 19 bearing symbol 25 is deformed into its proper recess 22. The sleeve 13 is then threaded to a position wherein effects snug interengagement of the end of tube 11, washer 19 and shoulder 14 with the alignment symbol 26 15 on the shoulder in alignment with the symbol 25 which will effect proper alignment of the ports 23 and 24. The remaining tabs 20 of lock washer 19 are now deformed into the recesses 21 on shoulder 14 thus interlocking the sleeve 13 and tube 11 with ports 23 and 24 aligned and piston head 28 positioned in the sleeve as shown in Fig. 1. Finally the valve cage 38 with its attached valve 35 is threaded on the forward end of sleeve 13 by interthreading the threads 43 thereof with the threads 44 on sleeve 13 until the valve 35 is in proper adjustment which may be determined by the position of spring detent 46 relative to the recesses 49 on shoulder 14.

30 The weapon having the regulator assembled as above described and otherwise conditioned for functioning will function as follows with regard to the regulator: Piston 27 occupies the position shown in Fig. 1 in the "ready to fire" condition of the weapon. Upon firing a chambered cartridge the gases of explosion will propel the projectile through the bore of the barrel and when they reach port 23 a portion thereof will enter the port and be admitted to chamber 45. Since chamber 45 is designed to constrict expansion in a ratio proportioned to the displacement of piston head 28 and rate of escape of gas through port 37 there will be no abrupt expansion of gas in the chamber and then sudden arrestation of expansion to impart an undesirable shock, impact or thrust to the weapon, but rather an expansion that must gradually overcome loss of pressure by reason of escape of gas through port 37 thereby necessitating that the expansion impart a gradual accelerating force to the piston wherein its inertia and load will gradually be overcome in contrast to the instantaneous acceleration and accompanying shock obtained when the expansion ratio of this invention is not provided. After the gas has built up a sufficient pressure in chamber 45 against escape through port 37, the piston 27 begins its recoil stroke under gradual uniform acceleration, as the pressure build up is in proper ratio to the piston displacement and gas escape from port 37 to accomplish this predetermined end. The piston will travel in recoil performing such work as it is designed to do in the weapon and be returned in counterrecoil in any conventional manner to its initial position shown in Fig. 1. Owing to the character of the material of the piston ring 29 it will broach any deposition tending to accumulate on the walls of sleeve 13 within which it reciprocates and deposit the broached material in chamber 45. Likewise the ledge 31 in the plane of the forward end 35 of the piston in the latter's normal position of rest will assist in the scavenger action of the piston ring by presenting an edge to the piston ring and obstruction to direct flow of gases between the piston ring and sleeve. Loose particles collecting in chamber 45 due to the scavenger action

of piston ring 29, or otherwise, will be removed from the chamber with the gases flowing through port 37. To regulate the cyclic rate of the gun within limits, or for various powered ammunitions, the operator need only adjust the valve 35, with respect to its seat 17 by rotating the valve cage 39 on sleeve 13.

It is to be understood that while the sleeve 13 is described as being attached to tube 11 by a threaded connection that such description is only by way of illustration since any suitable means for demountably interlocking these two elements may be employed although the threaded connection is preferred since by the arrangement shown the threads are not subjected to freezing by action of deposits made by the gas.

In Fig. 4 a modified form of valve 35' which may be used in lieu of valve 35 is shown. This valve has a cylindrical sleeve 50 extending from its truncated end which is adapted to be snugly received within the chamber 45. Ports 51 establish communication between the interior of the sleeve and exterior and a port is provided centrally through the valve identical with the port 37 of valve 35. Valve 35' is secured to valve cage 39 in the same manner as valve 35. When the valve 35' is used for valve 35 the regulator is more easily cleansed inasmuch as it is only necessary to remove the valve 35' from sleeve 13 and remove carbon or other deposits of fouling from the interior of the sleeve 50 instead of from the chamber 45.

Fig. 5 discloses a modified form of the regulator applied to the end portion of a gas cylinder tube 11 having a piston 27 therein. A plug 52 having an enlarged outer end 53 is externally threaded and received in complementally threaded relation within the end of tube 11. The plug 52 has its rear end portion longitudinally forwardly bored on increased diameters to receive the piston head 28' of the piston and form a gas chamber 45'. Forwardly of the chamber the plug is formed with a longitudinally extending centrally positioned port 54 comprised of the sections 55, 56 and 57, respectively. Section 55 is joined to the section 57 of largest diameter by intermediate section 56 of smallest diameter and at the zone of junction of section 56 with sections 55 and 57 the latter sections are properly flared to eliminate turbulence in the flow of gas from section to section. Section 55 and port 58 combine to compel a right angle turn of gas entering chamber 45' from port 58 thereby reducing "climb" of the weapon. Section 56 is of such size as to constrict porting from chamber 45' as to compel a pressure build up in accordance with the manner described with regard to the regulator of Fig. 1 and section 57 is sufficiently large in diameter to eliminate a back pressure being built up therein that would affect porting from section 56.

The plug is formed with a transverse opening 59 through its enlarged head 53 to receive a locking pin having resilient legs 60 adapted to frictionally secure the pin in the opening and a head 61 adapted to seat within a recess 62 in the shoulder 53 and end of tube 11 for interlocking the latter.

In this form of the invention the piston head 28' is formed to have a piston ring 29' consisting of three elements of larger diameter integrally joined with intermediate elements of smaller diameter and as in the case of the form shown in Fig. 1 the piston ring 29' is formed of a chromium-cobalt-tungsten steel alloy while the plug 52 is formed of an aluminum-bronze alloy. In

this form of the invention adjustment is secured by presenting the port 58 of desired size to the port through tube 11 leading to the barrel, otherwise the regulator functions in similar respect to the one disclosed in Fig. 1.

5 In the modification shown in Fig. 6 there is disclosed a regulator very similar to the one disclosed in Fig. 1 provided with the valve of Fig. 4, however, in this modification the valve cage 39 of Fig. 1 has been omitted with corresponding changes in the valve 35' and sleeve 13. The sleeve 13' which is of stepped outside diameters is secured and demountably locked to the tube 11 as in Fig. 1. Forwardly of the portion of 10 smallest outside diameter the sleeve is formed to receive a spring detent 63. The valve 35' is externally threaded to be received by the internal threads formed in the sleeve 13' and is adjustable to completely seat the valve so that gas can 15 escape from chamber 45' by way of port 37 only, or by way of ports 51 past the valve. The valve will be retained in position of adjustment by detent 63 which engages recesses in the valve 35'. This modification will function the same as the form of Fig. 1.

20 In the forms of the invention, illustrated in Figs. 1 to 4 and 6, the volume of the gas chamber is sufficiently large to maintain the temperature of the gases collected therein high enough to effect combustion of combustible particles or similar matter obtaining admission to the chamber which reduces or eliminates flash of gases ported through or past the valve.

25 Having now described the invention as embodied in a present preferred form I claim:

30 1. A gas regulator for an automatic gun comprising a sleeve having a through cylindrical bore adapted to receive a piston for reciprocable movement in one end portion and being formed with an axially disposed conical valve seat at its opposed end portion, a piston reciprocably mounted in said one end portion of the sleeve, a valve adapted to coact with the valve seat to adjust the passage from the bore past the valve, a valve cage for said valve adjustably mounted on the sleeve having a plurality of circularly arranged ports open to the atmosphere, means securing the valve cage to the sleeve for adjustment to regulate said passage, said sleeve having a port 35 35 therein intermediate the piston and valve adapted to be placed in communication with the bore of a barrel.

40 2. A gas regulator comprising a sleeve having a through cylindrical bore reduced in diameter for a portion of its length adjacent one end portion to receive a piston for reciprocable movement in the bore portion of reduced diameter, the bore of the sleeve adjacent its end portion opposed to the portion of reduced diameter being outwardly 45 flared to provide a truncated conical valve seat, a valve having a truncated conical surface complementary to said valve seat provided with an axially disposed portion of reduced diameter projecting from the base thereof, said valve being 50 formed with an axially disposed port, a valve cage having an inturned flange adapted to receive the reduced projection of said valve and having a plurality of ports in said flange, means affixing the reduced portion of the valve to said flange, 55 means for adjustably securing the valve cage to the sleeve with the valve seat and complementary surface of the valve disposed to regulate the passage from the bore through said ports in the inturned flange of the valve cage, said sleeve 60 being formed with a port disposed intermediate 65 70 75

the reduced portion of the bore and valve seat for admission of gases.

3. A gas regulator comprising a sleeve having a through cylindrical bore reduced in diameter for a portion of its length adjacent one end portion to receive a piston for reciprocable movement in the bore portion of reduced diameter, the bore of the sleeve adjacent its end portion opposed to the portion of reduced diameter being outwardly flared to provide a truncated conical valve seat, a valve having a truncated conical surface complementary to said valve seat provided with an axially disposed portion of reduced diameter projecting from the base thereof, said valve being formed with a longitudinally extending centrally disposed port terminating in an outwardly flared entrance, a cylindrical valve cage having an in-turned flange at one end formed with circumferentially arranged ports, said flange being adapted to receive the portion of reduced diameter of said valve, means affixing the portion of reduced diameter of said valve to said in-turned flange with the valve disposed within the cylindrical portion of the valve cage, means for adjustably securing the valve cage to the end portion of the sleeve adjacent said valve seat in substantially fluid sealed relation with the complementary surfaces of the valve and valve seat arranged to coact to regulate passage from the bore of the sleeve through said ports in the in-turned flange of the valve cage upon adjustment of the cage, means on said valve cage adapted to coact with a portion of the sleeve to retain the cage in adjusted position, said sleeve being formed with a port disposed intermediate the reduced portion of the bore and valve seat for admission of gases.

4. The structure of claim 3 wherein said means on the valve cage for retaining it in adjusted position comprises a spring detent having a free finger secured thereto and the portion of the sleeve with which it coacts comprises an external shoulder thereon intermediate its ends provided with spaced recesses adapted to receive the finger of the detent.

5. The structure of claim 3 wherein said valve also comprises a cylindrical sleeve extending from its truncated end portion fitting snugly within the bore of said first recited sleeve and having ports formed therethrough adjacent the junction with the valve.

6. In a gas actuated automatic weapon, a gas regulator including a gas tube cylinder having a gas admission port in its wall, a tubular sleeve demountably secured to the muzzle portion of said cylinder and having a gas admission port

adapted to register with the port in the gas tube cylinder, an external shoulder on the sleeve intermediate its ends, means for aligning said ports and interlocking the sleeve and gas tube cylinder comprising recesses in the shoulder and adjacent the end of the gas tube cylinder, a lock washer fitting between the shoulder and said cylinder and having a tab deformable into a recess in the gas tube cylinder, an alignment symbol on the tab rendered visible when the tab is deformed into a recess in the cylinder, an alignment symbol on the shoulder, said symbols being co-related and adapted to be brought into registry to indicate the registration of said ports, and other tabs on the lock washer adapted to be deformed into recesses in the shoulder to further augment the interlocking of the sleeve and gas tube cylinder.

7. The structure of claim 6 wherein the dimensions of said symbol bearing tab and its corresponding recess do not correspond with the other tabs and their corresponding recesses; whereby an operator will always be compelled to deform the symbol bearing tab into its proper recess.

8. A gas regulator comprising a tubular sleeve having its outside diameter stepped from an intermediate zone to one end, a piston mounted for displacement within its bore adjacent the end portion of smallest outside diameter, said sleeve being formed with a forwardly and outwardly truncated conical valve seat adjacent its portion of greatest outside diameter and being internally threaded inwardly of the valve seat, a valve having a truncated conical surface complementary to said valve seat and an integral tubular portion projecting from its truncated end, said valve having ports providing for communication between the interior of the projection and exterior of the valve and disposed in inter-threaded relation to the threads in the sleeve with the complementary surface of the valve and valve seat related to coact to regulate the passage from the sleeve through the projection, ports and between said complementary surface of the valve and valve seat to atmosphere upon adjustment of the valve in the sleeve, and said sleeve having a radial gas port therein intermediate the inner end of the projection and the end of the inner stroke of the piston.

9. The structure of claim 8 wherein the portion of the sleeve adapted to receive the piston is of reduced interior diameter from the end thereof to a plane coinciding with the end of the inner stroke of the piston.

10. The structure of claim 1 wherein said valve is provided with an axial port.

SAMUEL G. GREEN.
